PARACHUTE PACK

Lewis Dearstyne, Upper Darby, Pa., and Joseph J. Rutkowski, Trenton, N. J., assignors to Switlik Parachute Company, Trenton, N. J., a partnership of New Jersey composed of Stanley Switlik, Walter Switlik, Richard Switlik, and Lottie Switlik

Application November 3, 1943, Serial No. 508,778

10 Claims. (Cl. 244—148)

This invention relates to a parachute pack.

An object of the invention resides in the provision of a pack wherein at least a portion of the wall of the container is resiliently flexible, transparent and preferably water repellent.

A further object of the invention resides in the provision of a pack that includes a cover and a tray, wherein the tray is resiliently flexible and transparent and yet possesses sufficient rigidity to maintain the remaining elements of the pack in their proper positions within the container and the container in its proper form.

A further object of the invention resides in so constructing a parachute pack that the flying personnel may fairly inspect the pack without the removal of the container.

A still further object of the invention resides in so locating the packing data card and so constructing the container that it will be impossible to make entries upon the packing data card without disassembling the pack and yet it will be possible to view the card without disassembling the pack.

As other objects of the invention will appear as the description progresses, it is thought that it is unnecessary to here point them out in detail.

In the drawing, in which the invention is illustrated as embodied in one type of pack:

Figure 1 is a perspective view of such a pack;
Figure 2 is a section on line 2—2 of Figure 1; and

Figure 3 is a section on line 3—3 of Figure 1.

The pack illustrated includes the usual canopy 1, to which the suspension lines 2 are attached, which suspension lines 2 are also attached to the lift webs 3 by means of the usual metallic fittings 4. In addition to the above elements the pack includes a flexible cover 5 which may be made of water repellent fabric such as canvas, drill or the like. A tray 6 cooperates with the cover 5 to enclose the remaining elements of the pack and the two are held together, releasably, by a ripcord 7.

This tray 6 is made of a transparent, resiliently flexible plastic material such, for instance, as Lucite. Around the edge of the transparent material a frame 8 is secured, which frame is also formed of a plastic material of such form and dimensions that the frame itself will be substantially rigid. As disclosed in Figure 2 the frame is provided with a groove 9 in which the edge of the cover 5 and the ripcord 7 seat.

Along opposite edges of the tray, and on the inside surface thereof, pockets 10 are formed. These pockets are preferably formed from a continuous tape which is detachably secured to the

tray by separable fasteners 11, the pockets being for the purpose of maintaining groups of suspension lines in position within the container when the pack is in its packed condition.

- 5 On the inner face of the tray 6 a pocket is formed by a flap 12 which is secured to the inner face of the tray. This pocket may be of a transparent, translucent or opaque material but we prefer to make it of a transparent material. The 10 pocket is adapted to receive and support a packing data card 13 on which, in accordance with today's practice, the data pertaining to each successive packing of the chute is entered at the time of packing.
- 15 It is, of course, the practice in building the parachute packs to so relate the bulk of the canopy, suspension lines, lift webs and attachments to the size of the container that when the former are packed within the latter pressure will be exerted on the former. We maintain this relationship in the pack of this application.

The tray is preferably flat, that is to say, the transparent closure portion 14 thereof lies substantially in a single plane when not under stress. 25 When, however, the container is packed the contents thereof will tend to force the closure 14 outwardly because of the anchoring of the cover to the tray by the ripcord, with the result that the closure which is anchored to the frame 8 will react to hold the contents of the container in place; that is to say it will maintain the canopy properly folded, the suspension lines in their orderly bundled condition and in the pockets and will substantially prevent movement of these elements as well as the portions of the lift webs that lie within the container. Additionally the packing record card 13, which is placed on the inside of the container within the pockets 12, will be held in position and will be prevented from becoming entangled with the suspension lines or obscured thereby.

While the tray we have described performs, among others, those functions we have above pointed out, it performs other additional and important functions. Being transparent, the tray of the container permits the flying personnel to make an inspection, at any time during use, to an extent which will permit the determination of the presence of the essential elements of the parachute and to determine to a great extent their condition and arrangement. Moreover, it insures the re-packing of the chute each time an entry is made upon the packing record card for the card is inaccessible to the packer until

the container has been opened. Thus false entry on the card is prevented.

The tray of the character described may, of course, be subjected to temperature and other climatic changes, and being free of metal will not corrode and consequently will not only have a longer life but will insure the proper functioning of the parachute.

It will of course be understood that the invention may be incorporated in seat, chest or back packs, either of the attached or attachable types.

While we have illustrated and described a particular embodiment of our invention we do not wish to be limited to the details of construction except in so far as those details are included in the claims.

What we claim is:

1. A parachute pack including a container consisting of a cover and a tray, a canopy, suspension lines, and lift webs, the tray having a substantially rigid frame and a resiliently flexible, transparent sheet of plastic material attached to and closing said frame. 20

2. In a parachute pack including a container consisting of a cover and a tray, a canopy, suspension lines and lift webs, the tray having a substantially rigid frame and a resiliently flexible, transparent sheet of plastic material attached to and closing said frame, the frame having a ripcord receiving groove in the outer face thereof. 25

3. In a parachute pack including a container consisting of a cover and a tray, a canopy, suspension lines and lift webs, the tray having a substantially rigid frame and a resiliently flexible, transparent sheet of plastic material attached to and closing said frame, and a pocket for a packing data card on the inner face of said sheet of material. 30

4. In a parachute pack including a container consisting of a cover and a tray, a canopy, suspension lines and lift webs, the tray being normally flat and formed of a transparent, resiliently flexible material. 40

5. In a parachute pack including a container consisting of a cover and a tray, a canopy, suspension lines and lift webs, the tray being normally flat and formed of a transparent, resiliently flexible material, and a pocket on the inner surface of said tray for receiving a packing data card. 45

6. In a parachute pack including a container

consisting of a cover and a tray, a canopy, suspension lines and lift webs, the tray having a substantially rigid frame, a normally flat sheet of resiliently flexible, substantially non-stretchable, transparent, plastic material attached to and closing said frame. 5

7. In a parachute pack including a container consisting of a cover and a tray, a canopy, suspension lines and lift webs, the tray having a substantially rigid frame, a normally flat sheet of resiliently flexible, substantially non-stretchable, transparent, plastic material attached to and enclosing said frame, and a pocket on the inner face of said sheet of material for receiving a packing data card. 10

8. In a parachute pack including a container consisting of a cover and a tray, a canopy, suspension lines and lift webs, the improvement which includes making a portion of the container of a sheet of transparent, resiliently flexible, plastic material which is normally flat, whereby the tendency of the sheet of material to return to its flat condition when flexed, will assist in maintaining the canopy, suspension lines and lift webs in position within the pack and the interior of the pack may be observed. 15

9. In a parachute pack including a container consisting of a cover and a tray, a canopy, suspension lines and lift webs, the improvement which consists in constructing a portion of the pack of a transparent, resiliently flexible sheet of material, and in providing the interior surfaces of the sheet of material with a pocket for receiving a packing data card whereby access to the pocket is prevented except upon disassembly of the container. 20

10. In a parachute pack including a container comprising a back and a cover, a canopy, suspension lines and lift webs, the back including a normally flat, transparent, resiliently flexible portion, the suspension lines and lift webs, when packed, lying against said back and partly adjacent said transparent resiliently flexible portion thereof said normally flat transparent, resiliently flexible portion being constructed and arranged to exert pressure upon the packed canopy and suspension lines to assist in maintaining the said canopy and suspension lines in position within the container. 25
